UNITED STATES PATENT OFFICE.

WILLIAM F. GRUPE, OF PHILADELPHIA, PENNSYLVANIA, ASSIGNOR TO C. F. RUMPP & SONS, INC., OF PHILADELPHIA, PENNSYLVANIA, A CORPORATION OF PENNSYLVANIA.

TRAVELING CASE FOR WATCHES.

Application filed March 28, 1921. Serial No. 456,090.

To all whom it may concern:

Be it known that I, WILLIAM F. GRUPE, a citizen of the United States, residing in Philadelphia, Pennsylvania, have invented 5 a Traveling Case for Watches, of which the following is a specification.

This invention relates to traveling cases for watches and clocks, the object of the invention being to provide a case of this type 10 comprising certain novel and improved features hereinafter fully set forth and described.

One form of my invention is illustrated in the attached drawings, in which:

15 Figure 1 is a side view of the case closed; Fig. 2, is a front view of the opened case, and

Fig. 3, is an edge view of the case opened and set up.

20 With reference to the drawings, the invention comprises a pair of substantially rectangular frames 1 and 2, of metal in the present instance, the frame 1 having at one end an extension 3 which is adapted to

25 fit between two spaced extensions 4, 4, at one end of the frame 2, and the said extensions 3 and 4 having suitable eyes or tubes 3^a and 4^a at their extremities, formed in the present instance by bending over the said

30 extremities, through which passes a rod or pin 5 establishing a hinged connection between the said frames 1 and 2.

Suitably secured to the frames 1 and 2 are, in the present instance, fabric covering 35 elements 6, 6, which form the respective enclosing sides of the casing, and at the outer end of the frame 1 in the present instance and in the interior of the case is a suitable hook 7 over which the stem ring of a watch 40 may be passed, or any other suitable clamping element may be employed for supporting the watch. Suitable interengaging locking

elements 8 and 8^a are provided at the free ends of the frames 1 and 2 respectively for retaining the frames together when the case 45 is closed, said elements being disengageable by means of a projecting portion 8^b of the element 8.

In setting up the case, the frame 1 is turned backwardly as far as it will go 50 against the frame 2, and the case is placed in the position illustrated in Fig. 3, the frame 2 forming a pedestal for the frame 1 which is retained in an inclined, more or less upright, position. It will be noted, by 55 referring to Fig. 3, that the adjacent end pieces of the frames 1 and 2 are made sufficiently thick to bring them into contact when, in turning back the frame 1, the latter has assumed the desired inclination to the 60 horizontal. In other words, the said frame 1 is retained in the desired inclined position entirely by reason of the engagement of the said adjacent end pieces of the frames, there being no necessity for special struts or 65 supports of any sort.

By this arrangement of elements, a greatly simplified and at the same time efficient case is provided.

I claim:

A casing comprising a pair of substantially rigid, rectangular frames hinged together at one side and adapted to lie in juxtaposition, flexible backings for the frames, means for securing the frames in 75 the juxtaposed position, means whereby when the frames are opened out and folded backwardly engagement of the hinged sides retains the frames in a position forming an acute angle between the backs, and a watch-suspending element carried by one of the frames. 80

WILLIAM F. GRUPE.
